(57) **CLAIM**

The ornamental design for a drug delivery device with
insertion mechanism button safety, as shown and described.

DESCRIPTION

FIG. 1 is a top perspective view of a drug delivery device
with insertion mechanism button safety showing our new
design;

FIG. 2 is another top perspective view thereof;

FIG. 3 is a bottom perspective view thereof;

FIG. 4 is a top plan view thereof;

FIG. 5 is a left side elevational view thereof;

FIG. 6 is a right side elevational view thereof;

FIG. 7 is a front elevational view thereof;

FIG. 8 is a back elevational view thereof; and,

FIG. 9 is a bottom plan view thereof.

The broken line showing of the drug delivery device with
insertion mechanism button safety is included for the purpose
of illustrating portions of the “article” and forms no
part of the claimed design.
